[57] CLAIM

The ornamental design for a vest for nurses, as shown
and described.

DESCRIPTION

FIG. 1 is a front elevational view of a vest for nurses,
showing my new design;

FIG. 2 is a rear elevational view thereof;

FIG. 3 is a right side elevational view thereof, the left
side being a mirror image;

FIG. 4 is a perspective view thereof; and

FIG. 5 is an enlarged fragmentary view of the portion
indicated by circle 5 in FIG. 4.

FIG. 2

FIG. 1

FIG. 4

FIG. 3

FIG. 5

UNITED STATES PATENT AND TRADEMARK OFFICE
CERTIFICATE OF CORRECTION

PATENT NO. : D 311,085

DATED : 10/9/90

INVENTOR(S) : Moen

It is certified that error in the above-identified patent and that said Letters Patent is hereby corrected as shown below:

ON THE TITLE PAGE

In the Description, immediately following the description of Figure 5,

insert   --The broken line showings of rectangular objects in the pockets are for
illustrative purposes only, and form no part of the claimed design.--

Signed and Sealed this

Twenty-first Day of April, 1992

Attest:

HARRY F. MANBECK, JR.

Attesting Officer

Commissioner of Patents and Trademarks
